[57] CLAIM

The ornamental design for a telephone instrument, as shown and described.

DESCRIPTION

FIG. 1 is a top perspective view of a telephone instrument showing my new design, with the handset in a separated position;

FIG. 2 is a top plan view thereof; and

FIG. 3 is a top perspective view thereof, with the handset in an alternate position.

The undisclosed rear is plain and unornamented.

FIG. 1

FIG. 2

FIG. 3
